UNITED STATES PATENT OFFICE

159,429

SCRAPER

Robert W. Martin, Vancouver, Wash.

Application March 29, 1948, Serial No. 145,421

Term of patent 3½ years

(Cl. D39—1)

To all whom it may concern:

Be it known that I, Robert W. Martin, a citizen of the United States, residing at 2209 East Eighth Street, Vancouver, Clark County, in the State of Washington, have invented a new, original, and ornamental Design for Scraper, of which the following is a specification, reference being had to the accompanying drawing, forming a part thereof.

Fig. 1 is a side elevational view of a scraper, showing my new design;

Fig. 2 is a top plan view of the same;

Fig. 3 is a view in perspective of the same from one end; and

Fig. 4 is a view in perspective from the other end.

I claim:

The ornamental design for a scraper, substantially as shown.

ROBERT W. MARTIN.
